UNITED STATES PATENT OFFICE.

JOHN FRAME, OF SEARSPORT, MAINE.

MIXER.

1,155,907.

Specification of Letters Patent.

Patented Oct. 5, 1915.

Application filed November 14, 1913. Serial No. 801,044.

To all whom it may concern:

Be it known that I, JOHN FRAME, a citizen of the United States, residing at Searsport, in the county of Waldo and State of Maine, have invented certain new and useful Improvements in Mixers, of which the following is a specification.

My invention relates to mixers.

The primary object of my invention resides in the provision of an improved agitating means for a mixing device for efficiently beating eggs, mixing drinks or performing like functions, said agitating means embodying preferably two rotating elements, one rotatable in one direction to lift the material from the bottom of the vessel in which it is disposed and conveying it upwardly, the portion of the material being acted upon being thrown laterally therefrom due to the centrifugal force where it is again agitated by the other element which simultaneously rotates in an opposite direction, the remaining material which is carried toward the upper end being deflected through the medium of efficient means and thus directed toward the bottom of the receptacle to be subsequently acted upon for efficiently mixing materials.

A further object of my invention is to provide an improved means for holding the device in stationary position while the same is being operated.

A still further object of my invention is to provide a device that is simple in construction, efficient in operation, and one that can be manufactured and put upon the market at a minimum cost.

Other objects as well as the nature, characteristic features and scope of my invention will be clear from the following description taken in connection with the accompanying drawing and appended claims.

In the drawings: Figure 1, represents a side, elevational view, partly in section of my invention. Fig. 2, represents a plan view of my invention taken on line 2—2 of Fig. 1. Fig. 3, represents a fragmentary, sectional view of my invention taken on line 3—3 of Fig. 1.

Referring more particularly to the draw-

ings in which similar reference numerals designate like or corresponding parts throughout the different views, I provide a tubular shaft 1 on which is rigidly mounted a spiral agitator 2, comprising essentially in this instance a sleeve 3, provided with spiral blades 4, tapered toward their upper end. The shape of these blades vary for different work. For instance, if mixing cement or heavy material, the pitch of the blades would not be so sharp and the curve of the outer edges of the same would be more abrupt inwardly. When mixing lighter material for ordinary cooking, the pitch would be sharper and have less hook to the blades. Revolubly mounted above the spiral agitator 2, about the shaft 1, is a tubular sleeve 5, on the lower end of which is formed an annular collar 6. Formed integral with the under surface of the collar is a disk like supporting flange 7, having openings 8, through which extend the upper ends of the ribs 9, of the substantially conical cage agitator 10. By this arrangement it is to be noted that the supporting flange 7 constitutes a deflector having a diameter wider than the narrow upper end of the blade so as to direct the material lifted up from the bottom of a vessel, not shown, by the blades, toward the bottom in order that the material may be subsequently acted upon by the enlarged end of the blade. The cage agitator 10, which encompasses the spiral agitator consists essentially of downwardly depending ribs 9, formed of wire or the like material, the outer ends of which are preferably embedded as at 11, at spaced intervals in the periphery of the annular collar 6. The ribs are arranged in spaced relation with the spiral agitator 2, and terminate in loops 12, at their lower ends which are engaged upon the annular brace 13, made of similar material, and are substantially flush with the lower end of the spiral agitator. In order to strengthen the frame I have soldered or otherwise secured in uniform spaced relation intermediate the ends of the ribs, a plurality of annular braces 13.

For the purpose of actuating the agitators, I have provided the upper end of the

tubular sleeve 5, with a bevel gear 14, which is revolvably supported on the upper face of the lower arm 15, of the U-shaped bracket 16. The upper arm 17, of the bracket 16, is 5 provided at its outer end with a vertical extension 18, on the upper end of which is formed a suitable handle 19, and on the lower end of which is provided with a longitudinal chamber 20, in which is rotatably 10 mounted the upper end of the shaft 1. The shaft has fixedly secured thereto beneath the upper arm 17, of the bracket, a bevel gear 21. The body portion of the U-shaped bracket 16, is provided intermediate its ends with a 15 bearing sleeve 22, on which is rotatably mounted the horizontal shaft 23, carrying on its inner end a bevel gear 24, which meshes with the bevel gears 14 and 21. An arm 25 is rigidly secured to the outer end of the 20 shaft 23, which arm has formed on its free end a handle 26.

For the purpose of holding the device in a vertical position, and simultaneously allowing the device to be actuated, I have journaled the disk like head 28, formed on the lower end of the shaft 1, a foot 29, positioned in the cut-out portion 30, at the lower end of the spiral agitator. This foot consists essentially of an annular socket 31, and a 25 suction cup 32, formed of rubber, paper, or the like, secured to the bottom of the socket 31, by means of screws or the like fastening device 33, as shown in Fig. 3, of the drawing.

35 The operation of my device is as follows: One hand of the operator, (not shown) is placed upon the handle 19, pressure being exerted thereon to cause the suction cup 32 to grip the bottom of a receptacle or the like 40 (not shown), and the other hand of the operator (not shown), is engaged upon the handle 26. Upon actuation of this handle, the shaft 1, and the spiral agitator thereon is made to rotate in one direction and the 45 tubular sleeve 5, carrying the cage agitator 10, is made to rotate in the opposite direction by means of the bevel gear 24 meshing with the bevel gears 20, and 14, respectively. It will be noted that the spiral agitator will lift 50 the heavy material and sediment from the bottom and convey it upwardly, some of the material being thrown laterally from the blades due to the centrifugal force where it is engaged by the cage agitator 10, and 55 mixed. The material that is lifted upwardly finally strikes the supporting flange or deflector 7 and because of its arrangement the material is directed outwardly and downwardly where it falls to the bottom and 60 the vessel being engaged in its downward movement by the cage agitator, whereupon it is acted upon by the spiral agitator in the manner just described so as to continuously circulate the material for effectively mixing 65 the material.

It will be noted that I have provided a strong, thorough mixer and one that is particularly good for heavy mixtures as well as for paints and oils.

It will be obvious to those skilled in the art to which this invention relates that modifications may be made in detail without departing from the spirit or scope of the invention.

Having thus fully described my invention, what I claim as new and desire to secure by Letters Patent is:

1. A mixer including a tapered spiral agitator rotating in one direction, a deflector disposed above the narrow end of the agitator and rotating in an opposite direction, and a cage agitator carried by the deflector and encompassing the spiral agitator for cooperating with the spiral agitator in mixing material which is thrown from and lifted by the agitator.

2. A mixer including a shaft and tapered spiral agitator carried thereby, a sleeve disposed about the shaft above the narrow end of the blade, a disk-like deflector formed integral with the sleeve and having a diameter larger than the diameter of the upper end of the spiral agitator, a wire cage carried by the deflector and encompassing the spiral agitator, means for simultaneously rotating the spiral agitator in one direction for lifting material upwardly and for throwing some of the material therefrom while it is being lifted and for rotating said cage agitator in an opposite direction for agitating the material thrown from the spiral agitator, and said deflector causing the material lifted upwardly by the spiral agitator to return to the lower end of the spiral agitator to be subsequently acted upon by this agitator for efficiently mixing the material.

3. A mixer including a shaft, a spiral agitator rigidly mounted on said shaft, a sleeve rotatably mounted upon said shaft, a deflector upon said sleeve, a conical cage agitator supported by said deflector and encompassing said spiral agitator, said cage agitator including a plurality of longitudinally disposed ribs, annular braces for supporting said ribs, and means for operating said agitators in opposite directions.

4. A mixer comprising a shaft, a spiral agitator rigidly mounted upon said shaft, the blade of said spiral agitator tapering toward their upper ends, a sleeve rotatably mounted upon said shaft, a disk-like deflector formed upon said sleeve, an annular collar formed integral with said sleeve on the upper surface of said deflector, a substantially conical cage agitator including longitudinally disposed ribs and annular braces therefor, said ribs being secured in said collar and supported through openings in said deflector, said cage agitator encompassing said spiral agitator and conforming

substantially to the configuration of said spiral agitator, and means for simultaneously operating said agitators in opposite directions for continuously causing the material adjacent the shaft to be lifted upwardly and forced downwardly adjacent the cage agitator.

In testimony whereof I affix my signature in presence of two citizens.

JOHN FRAME.
